PAUL J. OSTRINGER, OF SCHENECTADY, NEW YORK.

DRAFTING INSTRUMENT.

1,111,174.

Specification of Letters Patent. Patented Sept. 22, 1914.

Application filed January 25, 1912. Serial No. 673,294.

To all whom it may concern:

Be it known that I, PAUL J. OSTRINGER, a citizen of the United States, residing at Schenectady, county of Schenectady, and State of New York, have invented certain new and useful Improvements in Drafting Instruments, of which the following is a specification.

The invention relates to such improvements and consists of the novel construction and combination of parts hereinafter described and subsequently claimed.

Reference may be had to the accompanying drawings, and the reference characters marked thereon, which form a part of this specification. Similar characters refer to similar parts in the several figures therein.

Figure 1 of the drawings is a plan view of my improved drafting-instrument. Fig. 2 is a cross-section of the same taken on the broken line 2—2 in Fig. 1. Fig. 3 is a cross-section of the same taken on the broken line 3—3 in Fig. 1. Fig. 4 is a plan view of the instrument adapted for drawing radial lines. Fig. 5 is a vertical cross-section of the same taken on the broken line 5—5 in Fig. 4. Fig. 6 is a plan view of a drafting-instrument embodying my invention in modified form. Fig. 7 is plan view of a corner of the triangle adapted to receive the adjustable pivot-pin.

The principal object of the invention is to provide a straight edge with means whereby it can be readily employed as a section-liner adapted for ruling parallel lines any given distance apart.

Other objects will appear in connection with the following description.

In carrying out my invention, I rotatively mount upon the straight edge a bearing-frame carrying wheels rotatively mounted in parallel planes, a plurality of said wheels projecting beyond the plane or surface of the straight edge to ride upon the drawing-board or paper, and one or more of said wheels having teeth for indicating the progressive movement of the instrument. Such an instrument is capable of many uses by the draftsman, and by rotatively adjusting the bearing-frame upon the straight edge to cause the wheels to travel at a greater or less angle to the line of the straight edge, a uniform progressive movement of the wheels can be made to advance the straight edge a predetermined greater or less distance as desired.

Referring to the drawings wherein the invention is shown in preferred form, 1, represents the straight edge, which may be of any known form, being shown in the convenient form of a triangle, of which the long side, 2, may for the purposes of this description be considered the line of ruling edge. The triangle is formed with a circular opening, 3, within which is rotatively mounted a bearing-frame, 4, having bearings for the horizontal shaft, 5, upon which are mounted spur-wheels, 6, 6, as shown in Fig. 1. The wall of the opening, 3, is formed with a circumferential rib, 7, and the bearing-frame is shown formed of two plates, 4^a and 4^b, which embrace the ribbed edge, 7, as shown in Fig. 2. The plates, 4^a and 4^b, are secured together by rivets, 8, which cause their edges to embrace the ribbed edge, 7, while permitting said plates to slide freely along said rib, while at one point said plates, 4^a and 4^b, are provided with a screw, 9, and nut, 10, whereby they can be clamped tightly upon the ribbed edge, 7, to lock the bearing-frame in fixed relation to the straight edge or triangle.

The wheels, 6, 6, as shown in Figs. 1 and 3, are formed with peripheral teeth or spurs adapted to travel along the drawing-board or paper with a step-by-step progressive movement, which is readily detected by the hand of the draftsman; and, when the wheels rest with two neighboring teeth on each wheel in engagement with the board or paper, the instrument will rest in a stable position. The spurs or teeth on the wheels, 6, are preferably spaced apart in conformity with some ordinary unit of measurement.

For use as a section-liner for ruling lines a distance apart equal to the distance between neighboring teeth on the wheels, 6, or a multiple of said distance between teeth, the bearing-frame is locked to the triangle with the shaft, 5, parallel with the line or edge, 2, and the instrument is placed upon the drawing-board or paper with the edge, 2, extending parallel with the desired direction of the section-lines. The instrument is then moved along the board or paper by the hand of the draftsman, at each movement one or more steps for each successive line to be ruled, said steps representing the distance between neighboring teeth on the wheels, 6, and being readily recognized by the touch of the draftsman. It will be understood that by adjusting the bearing-frame so that the

shaft, 5, will extend at more or less of an angle to the ruling-edge, 2, the same step-by-step movements of the wheels, 6, will cause the instrument to travel more or less obliquely to the line of its edge, 2, so that the progressive or advance movement of the ruling-edge, 2, will be less than that of the wheels 6. For example, if the shaft, 5, is arranged at an angle of 45 degrees to the 10 ruling-edge, 2, said edge, 2, will be advanced at each step of the wheels a distance equal to one-half the distance between neighboring teeth on the wheels.

In Fig. 1, the shaft, 5, is shown parallel 15 with the ruling-edge, 2, while in Figs. 4 and 6, it is shown at an oblique angle thereto.

The triangle and the bearing-frame may be provided with graduated scales, as shown at, 11 and 12, whereby the angular movements of the bearing-frame and shaft, 5, can be measured. One of said scales, as the scale, 11, on the body of the triangle, is preferably laid out in equal subdivisions of a circle, as degrees.

25 Another use of the instrument is to facilitate the ruling of oppositely and equally inclined lines such as those representing the sides of a tapered figure. For such use, the instrument having the shaft, 5, parallel 30 with the edge, 2, is placed with said edge, 2, parallel with the center line of the tapered figure, and the triangle is then rotated upon the bearing-frame until said edge, 2, is inclined to the desired degree for one side of 35 the figure, and the degree of this rotative or angular movement is noted by reference to one of the scales 11 or 12. With the triangle locked in this adjusted position upon the bearing frame, the instrument is 40 used for ruling one of the inclined sides of the figures. The triangle is then released from the bearing-frame and rotatively moved thereupon in the reverse direction until it is inclined to a corresponding degree, 45 as indicated by the scale, 11 or 12, whereupon it is again locked to the bearing-frame and used for ruling the opposite side of the tapered figure.

I have shown the bearing-frame provided 50 with a graduated edge, 13, extending through the axis upon which the bearing-frame rotates, whereby the instrument is adapted to facilitate subdividing the space between two parallel lines into any desired 55 number of equal spaces. For this purpose the scale along the edge, 13, corresponds with the spacing of the teeth on the wheels, 6, and the instrument is arranged obliquely across the space between the parallel lines 60 at such an angle that two points in the scale, 13, will lie upon the respective parallel lines, which points shall be separated by a number of spaces in the scale, 13, the same as, or a multiple of, the number of subdivisions desired. The triangle is then rota-

tively adjusted upon the bearing-frame with its edge, 2, coincident with one of said lines, whereupon the progressive step-by-step movement of the instrument will enable the draftsman to readily make the required subdivision, the subdivisions being indicated by one or more steps of the wheels as the case may be.

In Figs. 4 and 5, I have shown the instrument adapted for drawing radial lines. For such use the instrument is provided with a shouldered pivot-pin located at one corner of the triangle in line with the ruling-edge, 2, thereof, which pin is adapted to hold that corner of the triangle sufficiently above the surface of the drawing-board or paper to permit the nearer of the wheels, 22, to clear said surface, the triangle being adapted to ride upon the more remote of the wheels, 22, in its circular movement about the pivot-pin. I have shown the shouldered pivot-pin, 15, formed or fixed upon a spring-plate, 16, pivoted at, 17, upon an inclined top-surface, 18, on the body of the triangle, said inclined surface being formed with a seat or recess, 19, into and out of which the inner end of the plate, 16, can be sprung, and whereby the plate can be yielding held with its pointed end extended to engage the drawing-board or 90 paper, or with its pointed end extended inwardly and raised above the top-surface of the triangle. By extending the pointed end of the plate, 16, and inserting the same in the drawing-board or paper at the center of a circle, 20, the triangle can be caused to traverse a circular path around the center of the circle by a step-by-step movement, and can thus be used for the drawing of radial lines, or for laying off portions of the 105 circumference of the circle. In this use of the instrument, the bearing-frame is arranged with the shaft, 5, in line with the pivot-pin 15, and the step by step movement is indicated by the toothed wheel 23 and 110 click 24, as hereinafter set forth.

As shown in Fig. 1, the step-by-step movement is indicated by spurs or teeth on the same wheels upon which the instrument travels.

In Fig. 4, I have shown fixed upon the shaft, 5, wheels, 22, 22, upon which the instrument is adapted to travel, and I have shown fixed upon said shaft, 5, a toothed wheel, 23, adapted to be engaged by a click, 120 24, whereby the step-by-step movement of the instrument is indicated, the diameter of the wheel, 23, being smaller than that of the wheels, 22, whereby it is adapted to clear the surface of the drawing-board or 125 paper.

In Fig. 6 I have shown fixed upon the shaft, 5, a pair of wheels, 22, 22, upon which the instrument travels, and I have shown a third toothed wheel, 25, mounted upon the 130

bearing-frame, 26, parallel with the wheels, 22, 22, and also adapted to travel along the surface of the drawing-board or paper to indicate the step-by-step movement of the instrument.

5 For certain purposes of the invention, the bearing-frame may be rotatively mounted in any known manner upon the straight edge.

10 In the preferred form of my invention, the spacing teeth are formed on the wheels which engage the surface over which the instrument is moved, and these toothed wheels are located at an intermediate point between the ruling edge and the portion of 15 the body of the instrument which is most remote from the ruling edge. In the use of the instrument it is held and moved along the supporting surface by pressure of the tips of the fingers upon the body of the instrument adjacent to the ruling edge, and pressure of the thumb upon the portion of the body of the instrument most remote from the ruling edge, and on the opposite 20 side of the toothed wheels from the ruling edge. It will thus be seen that the rising and falling movement due to the teeth on the wheels is increased and accentuated at the point of the instrument engaged by the 25 thumb and most remote from the ruling edge. If the ruling edge be thus held against the supporting surface as the instrument is moved thereover, the user's thumb will be raised and lowered to a considerable 30 degree more than the axis of the wheels, thus enabling the user to more readily detect the step-by-step progress of the instrument.

What I claim as new and desire to secure 40 by Letters Patent is—

1. In a drafting-instrument, and in combination, a straight-edge; a bearing-frame rotatively mounted upon said straight-edge; a shaft rotatively mounted upon said bearing-frame; a pair of wheels mounted upon said shaft projecting slightly beyond the lower face of said straight-edge; means for securing said bearing-frame in fixed angular relation to said straight-edge and a 45 shouldered pivot-pin adapted to be removably located at one end of the straight-edge in line with its ruling-edge, and to support said end in an elevated position in which the nearer of said wheels will clear the surface upon which the instrument rests, said instrument having means for indicating step by step the movement of the instrument upon the other of said wheels around said pivot.

60 2. In a drafting-instrument, and in combination, a straight-edge having at one end an inclined surface provided with a seat; a bearing-frame rotatively mounted upon said straight-edge; a shaft rotatively mounted upon said bearing-frame; a pair

of wheels mounted upon said shaft projecting slightly beyond the lower face of said straight-edge; means for securing said bearing-frame in fixed angular relation to said straight-edge; a spring-plate pivoted upon said inclined end of the straight-edge, and adapted to be sprung into and out of said seat; and a shouldered pivot-pin carried by said spring-plate adapted in one position of said plate to project below the lower face of said straight-edge in line with its ruling-edge, and in another position of said plate to be supported above the upper face of said straight-edge.

70 3. In a drafting-instrument, and in combination, a straight-edge; a bearing-frame rotatively mounted upon said straight-edge; a shaft rotatively mounted upon said bearing-frame; and a plurality of wheels fixed upon said shaft projecting slightly beyond the lower face of said straight-edge, said instrument having toothed mechanism for indicating step by step the movement of the instrument on said wheels, said bearing-frame having a straight-edge extending through the axis of the bearing-frame and graduated to correspond with the spacing of said toothed mechanism.

75 4. In a drafting instrument, and in combination, a body having a ruling-edge, a bearing frame rotatively mounted upon said body, a plurality of wheels rotatively mounted in parallel planes upon said bearing frame and projecting slightly below the lower face of said body, said wheels having substantially V-shaped teeth arranged, those of one wheel opposite those of another wheel, respectively, and adapted to indicate step by step the progressive movement of the instrument, and means associated with said body adapted to hold a portion of the same 80 relatively stationary whereby the entire remainder of the body is adapted to swing around said stationary portion.

90 5. In a drafting instrument, and in combination, a body having a ruling edge, a bearing frame rotatively mounted in said body, a shaft rotatably mounted upon said bearing frame, a wheel mounted on said shaft projecting slightly below the lower face of said body, a pivot pin mounted on the body adapted to project below the same, said bearing frame being adapted to be turned into register longitudinally with said pivot pin, and means on said instrument for indicating the step by step movement of the instrument around said pivot on said wheel.

95 6. A drafting instrument comprising a body having a ruling-edge and a pointed end, said body having a raised inclined surface at the pointed end, a pivot pin mounted upon the raised surface of said body and adapted to project below the lower face of the body, said body having a depression in one 100

- end of the raised surface adapted to yieldingly receive one end of the pivot, a bearing frame adjustably mounted in the body and adapted to be moved into alinement with 5 said pivot pin, and a toothed wheel mounted upon said bearing frame and adapted for engagement upon a supporting surface whereby to impart a step by step movement to said body around said pivot.
- 10 7. In a drafting instrument, and in combination, a body having an edge of the desired contour, a bearing frame rotatively mounted in said body, a shaft rotatively mounted upon said bearing frame, a pair of 15 wheels mounted upon said shaft, said wheels being adapted to project slightly below the lower face of said body, a pivot pin adapted to project below the lower face of said body, and means for securing said bearing frame 20 in fixed angular relation to said body and in line with said pivot pin, said pivot pin being adapted to support one of said wheels clear

of the surface upon which the instrument rests, said instrument also having means for indicating step by step its movement upon 25 one of said wheels around said pivot.

8. In a drafting instrument, and in combination, a body having a ruling-edge, a bearing frame rotatively mounted upon said body, and a plurality of wheels rotatively 30 mounted in parallel planes upon said bearing frame and projecting slightly below the lower face of said body, said instrument having tooth mechanism for indicating step by step the movement of the instrument on said wheels, said bearing frame having a graduated straight-edge extending through the axis of the bearing frame.

In testimony whereof, I have hereunto set my hand this 6th day of January, 1912.

PAUL J. OSTRINGER.
